HEADER FOR BOTTLE FILLING MACHINES

Otto Powley, Sunderland, England, assignor to
 Robert Powley & Sons Limited, Sunderland,
 England, a company of Great Britain

Application August 8, 1941, Serial No. 406,059

1 Claim. (Cl. 226—124)

This invention relates to headers or bottle filling elements for bottle filling machines of the kind having a tank for containing the liquid to be fed into the bottle. These headers have sliding tubes and valves, operated by movements of the bottles as they pass through the machine, to control the flow of liquid from the supply tank into the bottles and the outflow of air from the latter as they are being filled, the sliding parts and valves of the headers being returned to their normal positions by springs or the like as the mouths of the bottles move down from their contact with the headers. The headers are usually connected to the bottom of the tank and extend partly within and partly beneath the bottom of the tank. Such machines work at a high rate of speed and owing to this high speed wear soon occurs between the rapidly moving sliding parts of the headers and their guiding means and liquid having access to such sliding parts exterior of the bottom of the tank can then escape or leak.

The object of my invention is to provide a dripless header wherein no glands are used with which the liquid can come in contact either when the machine is working or at rest and so prevent leakage by making it impossible for any liquid in the tank to have access to any sliding parts exterior of the bottom of the tank.

I attain this object by mechanism illustrated in the accompanying drawings in which:

Figs. 1 to 3 illustrate, in vertical section a header particularly suitable for filling bottles with non-gaseous liquids such as milk these figures showing the progressive movements of the sliding parts of the header operated by the rising of the bottle.

Fig. 4 is a modified form of a bottle filling valve of the header.

Fig. 5 is a diagram of the liquid supply tank.

In these drawings like parts are indicated by the same reference characters.

Referring to Figs. 1 to 3:

My improved header comprises a positively closed chamber situated below the plane of the tank bottom 1, the outside A of said chamber being in constant communication with the liquid in the tank. The lower part 3 containing the chamber is secured to a spider 2 immersed in the liquid and held between these two parts is a flexible transverse diaphragm 4 forming the top of the positively closed chamber.

The head of the spider forms a bearing for a slide tube 5 adapted to evacuate air from the bottle as it is being filled. This air tube is concentrically arranged within a slideable filler tube

6 of larger diameter for which a sleeve 1 of the lower part of the positively closed chamber forms a bearing in which it can slide, the sliding movement of each of the above tubes is spring governed by springs, respectively 8 and 9 as will be hereinafter described.

The upper end of the filler tube extends just through a central orifice of the diaphragm which is liquid-tight and is connected to said tube by 10 annular washers and packings 10 carried by the tube 6 or in any other suitable way so that the liquid which fills the spider and lies on the upper surface of the diaphragm 4 can only flow through the annular mouth of the filler tube formed between it and the inner air tube and flow down the annular space 11 between the two tubes.

The annular inlet of the tube 6 is freely open to the liquid in the tank.

The air tube 5 extends from the bottom of the 20 liquid supply tube through the latter and into the tank to a point above that of the level X of the liquid, that is to say into the air space above the liquid. The lower end of said tube is provided with a suitable valve 12 adapted to open and 25 close the outlet of the liquid supply tube, for instance the valve may be a conical or other suitably shaped member the seat for which is formed by the lower end of the supply tube thus forming an annular conical outlet port for the liquid, as shown in the drawings.

At the upper end of the air tube is an air outlet valve. This may comprise a valve casing 13 screwed on the top of the air tube 5 and having in its upper end a vent hole 14 normally closed 35 by a ball 15 pressed, by a spring 16 seated on the top of the tube against said vent. When the tube 5 is initially raised the valve casing moves upwards and the ball is pressed downwards against its spring on meeting a fixed seat 17 over the point of which the vent hole can pass so that the vent hole becomes open and the air from said tube can escape into the air space of the tank.

Fixed to the outer circumference of the liquid supply tube adjacent its lower end is a stop 18 45 for the mouth of the bottle 19. This stop is provided with a resilient cushion 20 against which the rim of the mouth of the bottle will abut and form an airtight joint when the bottle has been raised to the position for filling.

Between this stop and the base of the guide sleeve of the lower portion of the diaphragm chamber and surrounding the filler tube is the spiral spring 9 having a downward thrust and between the upper end of the filler tube and an adjustable abutment 22 arranged on the air tube

5 is the second spiral spring 8 surrounding the air tube, and having an upward thrust.

Above the bearing for the air tube in the head of the spider a second adjustable abutment 21 is arranged on the air tube.

The two abutments 21 and 22 limit the extent of the sliding movement of the air tube 5 in the upward and downward direction respectively and can be adjusted; accordingly as they are adjusted the period and degree of opening of the filler tube valve can be regulated.

When the bottle in its rising movement first presses under the bottle mouth stop as shown in Fig. 2 the filler tube 6 commences to move upwards thereby causing the air evacuation valve to start opening and at the continued rising movement of the bottle the liquid supply valve 12 will commence to open as shown in Fig. 3 and will close again when the bottle is filled and moves downwards from the bottle mouth stop 18 and allows the sliding members of the header to return to their normal positions under the action of the springs the air valve being now closed again as shown in Fig. 1.

The provision of the diaphragm 4 prevents access of the liquid to the sleeve bearing 7 beneath the tank for the filler tube so even if this bearing becomes worn no liquid can escape; it is to be remarked however that when the bottle is filled and moves downwards a small bead of the liquid may be formed on the bottom of the filler tube valve but this bead will adhere by suction to the bottom of the valve 12 until the next bottle of the series comes into position to be filled in its turn.

As diagrammatically shown in Fig. 5 the tank or liquid container in the machine is in the form of a cylinder 22a rotatable about its vertical axis, this conveys the header or headers connected thereto round in a clockwise or anti-clockwise direction. A tube 23 for admitting the liquid into the cylinder passes through the base thereof on the axis of the cylinder and forms a bearing member about which the cylinder can rotate. Within the cylinder is a non-rotatable horizontal disk or the like 24, which is above the level of the liquid in the cylinder and on the under face of this disk are two annular cam tracks 25 and 26 designed to open and close at determined intervals, the respective gas and liquid valves 25a, 26a of the header or headers as the latter travel round; the operating means for these valves contacting with said cam tracks whereby the valves are respectively opened or closed in a definite sequence. Instead of continuous cam tracks, individual abutments may be provided.

The disk 24 is carried by a vertical pipe 27 which is provided with a base 28 by which it is fixed to the fixed liquid supply tube 23, the pipe 27 being provided with orifices 29 through which the liquid from the supply tube 23 can flow into

the tank; leather washers 30 and 31 are provided to prevent leakage.

The liquid is supplied to the cylinder under pressure, the whole cylinder is air-tight.

5 In a modified arrangement shown in Fig. 4 a gas or air tube 43 extends up the centre of the filler tube and carries at its lower end the plunger 40 slideable in the valve sleeve 37 provided with liquor ports 38, said air tube extending through the plunger and in the position when the liquor ports 38 are open contacts with the opening of an air passage 44 and consequently in communication with the interior of the bottle being filled.

10 After the filling operation is completed, the bottle is held under pressure for a short while to allow the liquor to settle before allowing the header to return to its original position, so that the filled bottle can be removed.

Should a bottle burst or collapse the header 20 will immediately shut off and return to its original position thus avoiding waste in any shape or form, of gas or water, thus maintaining a steady pressure in the main filling cylinder.

15 The construction of my headers allows of easy 25 cleaning and simple dismantling and re-assembling of the parts, as there are no corners or recesses it allows considerably steadier filling and presents an exceedingly simple and efficient filling header which is operated solely by the bottle. The only mechanical means necessary is provision to lift the bottle.

20 What I claim as my invention and desire to secure by Letters Patent of the United States is:

The combination in a bottle filling machine of 25 a liquid supply tank having a floor formed by a flexible centrally perforated diaphragm, a vertical feed tube for conducting the liquid in said tank into a bottle, said feed tube being fixed gas and liquid-tight in the perforation of said diaphragm and having an opening at its upper end into said tank through which opening the liquid in the tank constantly has access, a fixed cup shaped member secured to said tank immediately below said diaphragm the outer rim of which is secured to the rim of said cup shaped member, said diaphragm cup shaped member and the outer periphery of said feed tube below said diaphragm forming a positively closed chamber of variable capacity into which the liquid cannot enter, a depending extension of said cup shaped member having a vertical bore in which said feed tube is slideable, an air tube within said feed tube, a bottle filling valve at the bottom end of said air tube, an air evacuation valve at the top of said air tube situated above the normal level of the liquid in said tank and a collar secured to the feed tube adjacent the lower end thereof with which the mouth of a bottle can engage to lift said feed tube to open said valves during upward movement of the bottle substantially as described.

OTTO POWLEY.
